UNITED STATES PATENT OFFICE

OSCAR H. WURSTER, OF CHICAGO, ILLINOIS

SPRAYING APPARATUS

Application filed August 19, 1925. Serial No. 51,119.

This invention relates to spraying apparatus for atomizing liquid or semi-liquid material and, by way of illustration, I have shown the invention as applied to the production of aerated or granular soap although it will be understood that the invention is applicable to many purposes other than the manufacture of soap. The object of this invention is to provide spraying apparatus 10 that will be convenient to operate and adjust, that will finely divide the material, that will not accumulate the material on the apparatus itself, that will efficiently mix the liquid material with the gaseous expulsion 15 medium and that will be of improved construction and operation. The invention is exemplified in the combination and arrangement of parts shown in the accompanying drawing and described in the following specification and it is more particularly pointed 20 out in the appended claims.

In the drawing:

Fig. 1 is a vertical sectional view of a spray nozzle forming a part of the present 25 invention;

Fig. 2 is a section on line 2—2 of Fig. 1; and

Fig. 3 is a sectional view of a spray tower having the nozzle in place therein.

30 There are numerous industrial operations or processes in which it becomes desirable or necessary to spray or atomize a fluid material with steam or air. The purpose is to finely divide the material so that it may be cooled, crystallized or dried in the chamber into which it is sprayed or atomized. Another purpose may be to incorporate with the material some air which will be retained after it has cooled, crystallized and dried. 40 Thus a light, fluffy, aerated, granular powder may be produced.

45 In atomizing a fluid material in the manner contemplated in the present invention the material in question and the air or steam under pressure are brought together in a mix-

ing chamber, mixed and ejected from a suitable orifice in the form of a spray. By projecting the mixture after it leaves the orifice against a dash plate or deflector plate the stream is further broken up and the particles 50 are further subdivided.

Among the mechanical problems that come up in atomizing a material are the bringing together of the material and air so that they will thoroughly mix, i. e. so that the air will 55 be incorporated with the fluid material; proper control of the air and the amounts of the material to be atomized; adjustment of the size of the orifice to meet varying conditions of pressure or available material or 60 desired capacities; and means for regulating and varying the distance of the dash plate from the orifice to give varying degree of impact and deflection as may be desired to obtain a certain fineness of material or a 65 definite spread of the sprayed material for its proper cooling, drying or crystallization. It is desirable to have the device so designed 70 that the means of securing the dash plate in place be such as not to afford a base for some of the solidified material to adhere to and gradually build up and thus interfere with the atomizing. When the dash plate is held in place with a yoke or with brackets some 75 sprayed material clings to this support and in turn gathers more material until a mass of material of considerable size and weight may ultimately build up, seriously interfering with operations and possibly resulting in damage to equipment in case of finally 80 breaking loose and falling. It is also desirable to design a device so that all wearing parts are easily renewable.

To accomplish the above I have designed a spray-nozzle, or spray-head, as shown. The 85 material and the air, both under pressure, are brought together through pipes 10 and 11 which are equipped with control valves 12 and 13 and enter the mixing chamber 14 at an angle so that the direction of flow is not great- 90

ly changed. I have used pressures of about 50 pounds but these pressures may be varied as conditions may warrant. The liquid or paste is pumped to the mixing chamber with 5 a pump 35 which produces rapid pulsations rather than a continuous unvarying stream. The liquid or thick paste is injected through inlet 15 into the mixing chamber 14 just in front of the compressed air inlet 16, so that 10 the air picks up the liquid as it flows out and carries it forward into the mixing chamber. In the mixing chamber a plate 17 is provided with suitable openings 18 through which the liquid and air must pass, thus insuring intimate contact and thorough mixing of liquid and air. In the orifice 19, I place an obstruction in the form of a sphere 20, cone or other suitable shape plug. This is attached 15 to a stem 21 which passes back through the body and to the top of the device and which is threaded so that by turning the stem the plug may be raised or lowered changing the size of the opening 20. It will be especially noted that this adjustment of the size of the 20 opening may be made while the nozzle is in operation and very simply by merely turning hand wheel 22 of the valve stem 21. A very fine and careful adjustment can thus be made and the actual effect of the adjustment can 25 be observed while and at the time the adjustment is made. If this adjustment or regulation must be made from the front of the nozzle by changing nozzle tips, or if the entire nozzle must be changed to change the size of 30 the opening, then the entire process must be interrupted, pumps stopped, etc. This involves inconvenience, loss of time and output and the amount of adjustment must be estimated inasmuch as the nozzle is not actually spraying when the adjustment is made. It may be necessary to readjust until the proper degree of regulation is obtained and thus much time may be consumed.

It will be noted that the dash or splash 45 plate 23 is adjustable also, so that its distance from the tip of the nozzle may be varied.

The dash plate 23 is secured to the extension of stem 21 which holds the regulation ball or plug 20 and thus being in the center 50 of the atomized material no material clings to it.

The nozzle tip 24 through which the material passes is a separate part screwed to the main body 25 of the device and may be replaced when worn. The regulating ball 20 and dash plate 23 are also separate parts, easily replaceable.

The entire device is so designed that the liquid and air are thoroughly mixed, that the 60 size of the atomized stream may be conveniently regulated while the nozzle is in operation and that the ejected stream of material is projected onto a dash plate so secured as not to offer a lodging place for solidified material. By this means a stream of fine par-

ticles is obtained in proper condition for cooling, drying or crystallizing, whatever the case may be. As the air and material are under pressure when ejected the explosive expansion of the air in intimate admixture with the liquid as it leaves the nozzle further assists in breaking up the stream into fine particles. Attached to the main body 25 is a threaded union 26 holding in place a bonnet 27. The bonnet is threaded to mesh with the threads on the stem 21 to provide the necessary regulation for the nozzle outlet. The bonnet cap 28 with a follower 29 and packing 30 provides proper seal for the stem in passing to the outside. The projecting portion of the stem is threaded and carries a wing nut 31 which may be screwed against the bonnet cap to lock the stem in a fixed position after proper regulation has been obtained. The main body of the device may also be provided with brackets or lugs 32 suitable for supporting and holding in place the entire nozzle.

In Fig. 3 I have illustrated the spraying nozzle installed in a spray tower for producing aerated or granular soap by the spraying processes described in my prior application, Ser. No. 661,361, filed September 7, 1923. The nozzle is supported in the tower 33 by means of a perforated floor or other open support 34. The air is introduced through the pipe 11 while the liquid soap is supplied through a pipe 10 through which it is forced by a pulsating pump 35. In practice, good results are produced by driving the pump at approximately 500 revolutions per minute the pump having four vanes so that the liquid soap is propelled in pulsations of approximately 2000 per minute but it will be understood, of course, that the invention is not limited to this feature although the nozzle is designed to co-operate with a pulsating pump to discharge the material in successive explosions.

I claim:—

1. A spray nozzle having a mixing chamber therein and having inlet openings disposed at oblique angles to the axis of said chamber to direct material into said chamber in the general direction of the axis thereof, one of said openings being disposed in advance of the other, the entrance of the rear opening to the mixing chamber being located at a point where the stream from said opening will meet the stream from the forward opening before either stream is deflected from the oblique direction of its opening so that material entering through the rear one of said openings will impinge against the side of the stream of material entering through the advance opening.

2. In combination, a spray nozzle having a longitudinally extending elongated mixing chamber provided with an inlet opening disposed at an oblique angle to the axis of said mixing chamber, means for forcing liquid

material under pressure through said opening in said mixing chamber, said mixing chamber having an inlet-opening thereto disposed in the rear of said first-named inlet opening and arranged at an oblique angle to the axis of said mixing chamber, the entrance of said openings being sufficiently close together to permit the entering streams therefrom to meet while retaining the angular direction of their respective openings.

10 means for directing gaseous material through said second-named inlet opening into said mixing chamber and against the stream of liquid material entering through said first-named inlet opening.

15 3. In combination, a spray nozzle having an elongated mixing chamber provided with an outlet orifice and having a pair of inlet openings arranged at oblique angles to the axis of said mixing chamber for directing material into said mixing chamber in the general direction of the axis thereof, one of said inlet openings being disposed in advance of the other, but sufficiently close thereto to permit the streams from said openings to meet before either is deflected from its entrance direction, means for introducing liquid material in a pulsating stream through said advance inlet opening, and means for introducing gas under pressure through the other of said inlet openings and against the stream of liquid material entering through said advance inlet opening.

20 4. In combination, a spray nozzle having an elongated mixing chamber therein provided with a discharge orifice at one end thereof and with a pair of inlet openings at the opposite end thereof, the diameter of said orifice being relatively small with respect to the diameter of said chamber, said inlet openings being arranged at oblique angles to the axis of said mixing chamber and disposed one in advance of the other, means for introducing liquid material into said advance inlet opening, means for introducing gaseous material under pressure into the other of said inlet openings, a stem extending through said mixing chamber and orifice, a body mounted on said stem and of smaller diameter than said orifice, said body being movable with said stem to regulate the discharge opening through said orifice, a baffle carried on said stem in advance of said discharge opening, said stem extending through said spray nozzle to the rear thereof and having threaded connection with the body of said nozzle, means for rotating said stem to adjust the opening of said orifice.

25 5. A spray nozzle having a longitudinally extending elongated mixing chamber provided with an inlet opening disposed at an oblique angle to the axis of said mixing chamber, said mixing chamber having an inlet opening thereto disposed in the rear of said first-named inlet opening and arranged at an

oblique angle to the axis of said mixing chamber, the entrance of said openings being sufficiently close together to permit the entering streams therefrom to meet while retaining the angular direction of their respective openings.

In testimony whereof I have signed my name to this specification on this 17th day of August, A. D. 1925.

OSCAR H. WURSTER.
